MASTER BRAKE CYLINDER FILLER

Frank H. Liljemark, Minneapolis, Minn., assignor to
Electro-Specialty Manufacturing Co., Minneapolis,
Minn., a corporation of Minnesota

Filed Jan. 28, 1963, Ser. No. 73,333

Term of patent 14 years

(Cl. D65—1)

FIG. 1 is a side elevational view of my new master brake cylinder filler.

FIG. 2 is an elevational view of the same taken from the opposite side.

FIG. 3 is a front elevational view of the same.

FIG. 4 is a rear elevational view of the same.

I claim:

The ornamental design for a new master brake cylinder filler, as shown.
